WORK ARM SEWING MACHINE

Frederick Lutz, Stuttgart, Germany, assignor to
 Union Special Machine Company, Chicago, Ill.,
 a corporation of Illinois

Application October 12, 1940, Serial No. 360,857
 In Germany October 18, 1939

14 Claims. (Cl. 112—220)

This invention relates to sewing machines. More especially, it has reference to sewing machines such as are used in the seaming of tubular articles such as garment sleeves and the like, and characterized by a work supporting arm along which the material is advanced incident to the sewing.

My invention is concerned with improvements which favor greater simplicity and economy in the construction and assembling of sewing machines of the kind referred to, as well as higher speed operation for capacity to better meet modern requirements as regards increased output.

One of the foregoing advantages is attained as hereinafter more fully disclosed, through operation of the needle and the associated or complementary stitch-forming element, i. e., the looper, from a single or common rotary actuator on the drive shaft of the machine, whereby the accurate synchronism in the movements of these instrumentalities is at all times assured.

Another of the advantages is attained through dynamic balancing of the drive shaft and by locating it low in the machine frame beneath the level of the parts actuated from it, with resultant improvement in the stability of the machine in operation at high speeds as a consequence of the absence of vibration.

Another of the advantages is secured by so constructing and arranging the interposed linkages by which the feeding instrumentality of the machine is actuated, so that these linkages are in endwise tension during their active strokes, rather than in endwise compression as ordinarily, with the result that they can be made much lighter than heretofore.

Another of the foregoing advantages is attained through construction of the work supporting arm as an integral part of the machine base, while the needle arm is separately formed and secured to the base in such a way that not only is the machining of the frame greatly expedited and the cost thereof materially reduced, but the assembling with it of the moving parts correspondingly facilitated.

Another advantage results from the formation of the machine frame with an oil-tight hollow in which the moving parts directly connected to the drive shaft are enclosed for the purpose of automatic lubrication by splash action, and with which a hollow in the work arm directly communicates so that the parts within it are also lubricated in the same way.

Other objects and attendant advantages will 55

appear from the following detailed description of the attached drawings, wherein

Fig. 1 is a view in side elevation of a sewing machine conveniently embodying the present improvements.

Fig. 2 is a fragmentary view showing the machine in longitudinal section.

Fig. 3 is a fragmentary view in elevation looking as indicated by the angled arrows III—III in Fig. 1.

Fig. 4 is a horizontal section of the machine, taken as generally indicated by the angled arrows IV—IV in Figs. 1 and 2.

Fig. 5 is a detail sectional view taken as indicated by the angled arrows V—V in Figs. 2 and 4.

Fig. 6 is a transverse sectional view of the machine, taken as indicated by the angled arrows VI—VI in Figs. 2 and 4.

Fig. 7 is a fragmentary view in cross section, taken as indicated by the angled arrows VII—VII in Figs. 2 and 4; and

Fig. 8 is a fragmentary detail sectional view, looking as indicated by the angled arrows VIII—VIII in Fig. 7.

With more specific reference to these illustrations, 10 designates the base of the machine which is hollow and of rectangular box-like configuration, and with which, in accordance with my invention, the horizontal tubular work supporting arm 11 is integrally formed. Mounted on the top of the base 10 and removably secured by screws 12, is the standard portion 13 of a needle arm 14 which overreaches the work supporting arm 11, and which at its free end terminates in a needle head 15. Integrally formed with the standard portion 13 of the arm 14, likewise in accordance with my invention, is a hollow upright laterally-offset column 16 which is of square cross-section and in effect constitutes an upward continuation of the hollow in the base 10, as shown in Figs. 2 and 6. The interiors of the base 10 and the column 16 are accessible upon removal of the screw-secured side and top cover plates respectively designated 17 and 18. From Figs. 2 and 6, it will be also observed that the lower part of the base 10 is utilized as a sump in which a supply of lubricating oil is maintained substantially at the level conventionally shown; and in order to prevent escape of oil splashed about within the machine frame as later on explained, compressible sealing gaskets 17a and 18a are interposed beneath the cover plates 17 and 18.

Confined to endwise reciprocation in vertically-spaced apertured guide lugs 20 and 21 on the

needle head 15 is a bar 22 whereto is secured, at the lower end, a needle 23 which is adapted to pass up and down through a throat plate 24 at the outer end of the work supporting arm 11. Through a link shown at 25 in Fig. 3, the needle bar 22 is connected to an arm 26 clamped on the front end of a horizontal oscillating or rock shaft 27, which is journaled in a bearing 28 on the needle head 15, and which extends rearward through a fixed bearing 29 in the front wall of the column 16 into the hollow of the latter. The needle head 15 also affords another pair of vertically-spaced apertured guide lugs 30 and 31 for a presser bar 32 which carries a presser foot 33 at its lower end. The presser bar 32 is subject to the downward pressure of a leaf spring 35, which, at its anchorage end, is supported by a projection 36 on the needle arm 14 and which is regulatable by a thumb screw 37. The presser foot 33 is liftable by a latch finger 38 adapted, when swung upward in Fig. 1, to engage beneath a stud projection 39 on a collar 40 secured to the presser bar 32. There is also provided a lever 41 by which the presser foot 33 may be controlled, said lever being fulcrumed at 42 on the needle arm 14 and having an extension 41a for connection to a knee press or foot treadle, not illustrated. By means of a spring shown at 43, the lever 41 is yieldingly held normally in contact with a stop stud 44 on the needle head 15.

Arranged to cooperate with the needle 23 in stitch formation within the free end of the work supporting arm 11 is a complementary instrumentality in the form of a looper 45, see Fig. 2, which is accessible upon removal of the closure cap shown at 46. As shown, this looper 45 is adjustably secured on the outer end of a horizontal shaft 47 which is journaled, with capacity for both oscillatory and endwise movement in bearings 48, 49 and 50, respectively within the hollows of the base 10 and the work supporting arm 11.

Incident to the sewing, the material being seamed is intermittently progressed along the work supporting arm 11 by a feed dog 51, the toothed portions of which operate upwardly through slots in the throat plate 24 in a well known manner. As shown, the feed dog 51 is affixed to the distal end of a horizontal bar 52 within the work supporting arm 11. Immediately inward of the bearing 50 for the looper shaft 47, the feed bar 52 is supported by a pair of short vertical links 53 whereof the lower ends are pivotally connected at opposite sides to the horizontal arm 54a of a bell crank 54 which is capable of oscillation about a transverse pin 55 engaged at its ends in upstanding laterally-spaced lugs 56 at the bottom of the work arm 11, see Figs. 2, 4 and 5. From Fig. 5 it will be noted that the central portion of the pin 55 on which the bell crank 54 is mounted is eccentric to the ends for a purpose later explained. At its rear end, the feed bar 52 is supported by virtue of being pivotally connected to the upward yoke arm 57a of a bell crank 57, whereof the hub is rotatively free on a crosswise extending axle pin 58 fixed in the opposite sides of the work supporting arm 11, but held against axial shifting between a pair of collars 59 on said shaft, Figs. 2 and 4. As shown in Figs. 1 and 2, the upper half 11a of the work supporting arm 11, is made so as to be separable and is secured by screws 60 for convenience of access to the parts at the interior when necessary.

Through connections about to be described, the

stitch forming and feeding instrumentalities of the machine all derive their movements from a drive shaft 61, which, see Figs. 4 and 6, extends crosswise of the machine base 10 and which is journaled in bearings 62 and 63 in the side walls of said base. On one of the protruding ends of the drive shaft 61 is mounted a combined hand and belt wheel 64 whereby the machine may be either manually or power operated. At its other protruding end, the drive shaft carries the rotor 65 of a suitable looper thread control means comprehensively designated by the numeral 66 in Fig. 4. Since this thread control means, per se, does not constitute a part of the present invention, no further reference need be made thereto herein.

Immediately inward of the bearing 62, the drive shaft 61 is formed with a crank 67 having a spherical surface 68 embraced by the lower end of a vertically disposed pitman 69. As shown in Figs. 2 and 6, the pitman 69 extends upward in the communicating hollows of the base 10 and column 14, and, at its top, embraces a ball 70a at the end of an arm 70 which is clamped to the rear (left hand in Fig. 2) end of the needle shaft 27. Through these provisions, it will be seen that the needle shaft 27 is oscillated for transmission of the necessary reciprocatory movements to the needle bar 22, and moreover that the pitman 69 is in endwise tension as the active or fabric piercing strokes are imparted to the needle, wherefore said pitman can be made comparatively light since it is not subjected under these circumstances to lateral flexure.

A second spherical surface 71 on the crank 67 of the drive shaft 61 is embraced by the lower end of another but shorter vertical pitman or link 72 whereof the upper end in turn embraces a ball surface 73a on a crank 73 formed on the looper shaft 47 in the interval between the bearings 48 and 49 for the latter, see Figs. 2, 4 and 6. As a consequence, it will be seen that the looper shaft 47 is oscillated for impartation of needle thread loop taking and shedding movements to the looper 45 incident to stitch formation. Thus, the oscillating movements of both the needle shaft 27 and the looper shaft 47 are, in accordance with my invention, derived from a common rotary actuator on the drive shaft of the machine.

Immediately inward of the bearing 63, the drive shaft 61 is further provided with a ball eccentric 75 which is embraced by one end of a horizontal strap link 76 whereof the other end is connected to a pivot 77 adjustable along the pendent extremity 78a of a double armed rocker 78. As shown in Figs. 2, 7 and 8, the rocker 78 is freely fulcrumed on an axle pin 79 extending crosswise of the hollow of the base 10 and held against endwise shifting on said pin between a pair of positionally-adjustable collars 80 and 81. The upwardly extending extremity 78b of the rocker 78 provides a socket for a ball 82 (Fig. 8) which is pierced for passage of a sleeve 83 rockable and axially shiftable on a cylindrical arm 84 on the looper shaft 47 (Fig. 7), the fulcrum hub of said arm being freely held between adjustable collars 85 and 86 (Fig. 2) on said shaft. As a consequence of the immediately foregoing arrangement, the looper shaft 47 is reciprocated endwise for impartation of the necessary needle-avoiding movements to the looper 45.

In the interval between the crank 67 and the eccentric 75, the drive shaft 61 is formed with two additional, adjacently-disposed ball eccentrics 87 and 88. The strap link 89 of the eccen-

tric 87 is connected at its outer end to a pivot stud 90 which is adjustable along a slotted arcuate arm 57b of the bell crank 57 to the end that endwise or feeding movements are induced in the feed bar 52 in a manner readily understood from Fig. 2. The ball eccentric 88 of the drive shaft 61 on the other hand, is embraced by a strap 91 which has a lengthwise adjustable arm 91a extending forwardly into the work supporting arm 11 and pivotally connected at its distal end to a vertical arm 54b of the bell crank 54, to induce, through said bell crank, the necessary rise and fall movements in the feed bar 52. By rotatively adjusting the pin 55, it will be apparent from Figs. 2 and 7 that the sphere of the feed rise may be varied as may be desired or required. It is to be especially noted here that during the active or fabric-advancing and concurrent rise movements of the feed dog 51 when the latter is opposed by the presser foot, the feed bar 52 and the link 91 are both under lengthwise tension. Thus these parts, too, can be made much lighter than ordinarily.

In order to stabilize the movements of the drive shaft 61, in its rotation, the latter is dynamically balanced by a counterweight shown at 93. Attention is directed to the fact that the drive shaft 61 is journaled low in the base 10 well beneath the level of the looper shaft 47, the feed bar 52 and the other parts which are actuated from it. As a consequence of this, the simplification of the machine and the use of fewer and lighter moving parts, higher speed operation is made possible with absence of vibration.

During the operation of the machine, the lower ball socket ends of the strap arms or links 69 and 72 and the counterweight 93 dip into the oil supply and disperse the oil within the communicating hollows of the base 10 and the column 16 to lubricate the various moving parts directly connected to the drive shaft 61, as well as the ball joint at 70a and the bearing 29 in the upper part of said column for the needle actuating shaft 27. Some of the splashed oil finds its way into the bearings 48 and 49 for the looper shaft 47, and also to the bearings 62 and 63 for the drive shaft 61 by way of ducts 95 and 96, see Fig. 6, which lead into the tops of the latter bearings. From Fig. 6 it will be further noted that pockets 97 and 98 are provided in the bearings 62 and 63 for retention of the trapped oil to insure adequate lubrication at all times, said pockets being closed by screw plugs 99 and 100 respectively which can be removed in the event that clogging should occur. Some of the dispersed oil, moreover, enters the hollow of the work supporting arm 11 to keep the parts enclosed therein properly lubricated also.

The construction of the machine frame in two parts, as described, is obviously favorable to ready machining, particularly in view of the ease with which access can be had to the hollows in the base 10 and the column 16 by way of the openings covered by the removable plates 17 and 18. Assembling, with the frame, of the moving parts is likewise greatly facilitated through provision of the side and top openings, and by virtue of the fact that the bearing 62 for the drive shaft 61 is made as a separable part of the machine base 10, as shown in Figs. 4 and 6.

Having thus described my invention, I claim:

1. A sewing machine comprising a frame with a work supporting arm along which the work is fed, and an overhanging needle arm; an oscillating needle shaft mounted on the needle arm; an oscillating looper shaft parallel with the needle shaft and extending lengthwise of the work supporting arm; and a drive shaft in the frame extending crosswise of the needle shaft and the looper shaft below them and having an eccentric actuator thereon from which said needle shaft and said looper shaft separately but simultaneously derive their oscillatory movements.
2. A sewing machine comprising a frame with a work supporting arm along which the work is fed, and an overhanging needle arm; an oscillating needle shaft mounted on the needle arm; an oscillating looper shaft parallel with the needle shaft and extending lengthwise of the work supporting arm; and a drive shaft in the frame extending crosswise of the needle shaft and the looper shaft below them, having thereon an eccentric actuator in the form of a crank from which said needle shaft and said looper shaft separately derive their oscillatory movements.
3. A sewing machine comprising a frame with a work supporting arm along which the work is fed, and an overhanging needle arm; an oscillating needle shaft mounted on the needle arm; an oscillating looper shaft parallel with the needle shaft and extending lengthwise of the work supporting arm and having a crank formed therein; a drive shaft in the frame extending crosswise of the needle shaft and the looper shaft below them and having an eccentric actuator thereon; an operating connection between the eccentric actuator on the drive shaft and the needle shaft; and a strap link connecting the crank of the looper shaft to said eccentric actuator.
4. A sewing machine comprising a frame with a work supporting arm along which the work is fed, and an overhanging needle arm; an oscillating needle shaft mounted on and extending lengthwise of the needle arm; an oscillating looper shaft parallel with the needle shaft and extending lengthwise of the work supporting arm; feeding means including a feed bar which extends lengthwise of the work arm; a drive shaft in the frame extending crosswise of the needle and looper shafts below them and having an eccentric actuator thereon from which the needle shaft and the looper shaft separately derive their oscillatory movements; and another eccentric actuator on said drive shaft from which the feed bar is actuated.
5. A sewing machine comprising a frame with a work supporting arm along which the work is fed, and an overhanging needle arm; an oscillating needle shaft mounted on and extending lengthwise of the needle arm; an oscillating looper shaft parallel with the needle shaft and extending lengthwise of the work supporting arm; feeding means including a feed bar which also extends lengthwise of the work arm; a drive shaft in the frame extending crosswise of the needle and looper shafts below them and having an eccentric actuator thereon from which the needle shaft and the looper shaft separately derive their oscillatory movements; another eccentric actuator on the drive shaft from which endwise or feeding movements are imparted to the feed bar; and a third eccentric on said drive shaft from which rise and fall movements are communicated to said feed bar.
6. A sewing machine comprising a frame with a work supporting arm along which the work is fed, and an overhanging needle arm; an oscillating needle shaft mounted on the needle arm; an oscillating looper shaft parallel with the needle

shaft and extending lengthwise of the work supporting arm; feeding means including a feed bar which also extends lengthwise of the work supporting arm; a drive shaft in the frame extending crosswise of the needle shaft and the looper shaft below them and having an eccentric actuator thereon from which both said needle shaft and said looper shaft derive their oscillatory movements; another eccentric actuator on the drive shaft; and means connecting the last mentioned eccentric actuator with the feed bar so that the latter is in lengthwise tension incident to the performance of its active or feeding stroke.

7. A sewing machine comprising a frame with a work supporting arm along which the work is fed, and an overhanging needle arm; an oscillating needle shaft mounted on the needle arm; an oscillating looper shaft parallel with the needle shaft and extending lengthwise of the work supporting arm; feeding means including a feed bar which also extends lengthwise of the work supporting arm; a drive shaft in the frame extending crosswise of the needle shaft and the looper shaft below them and having an eccentric actuator thereon from which both said needle shaft and said looper shaft derive their oscillatory movements; two additional eccentric actuators on the drive shaft; means connecting one of the additional rotary actuators with the feed bar so that the latter is in lengthwise tension incident to the performance of its active or feeding stroke; and means including a strap link operated from the other additional rotary actuator for imparting rise and fall movements to the feed bar, said link being also in lengthwise tension incident to communication of the lift movements to said feed bar.

8. A sewing machine comprising a frame with a work supporting arm along which the work is fed, and an overhanging needle arm; an oscillating needle shaft mounted on and extending lengthwise of the needle arm; an oscillating looper shaft in the frame parallel with the needle shaft and extending lengthwise of the work supporting arm; a drive shaft below said looper shaft crosswise of the latter having an eccentric actuator thereon; means connecting the needle and looper shafts to said eccentric actuator; and an oil-tight housing provided by the frame and enclosing the drive shaft and the parts directly connected thereto.

9. A sewing machine comprising a frame with a work supporting arm along which the work is fed, and an overhanging needle arm; a needle shaft mounted on the needle arm; a looper shaft parallel with the needle shaft extending lengthwise of the work supporting arm; a drive shaft journaled in the frame crosswise of the needle shaft and the looper shaft in a plane below the latter and having a rotary eccentric actuator thereon; and pitmans extending upward from said rotary actuator to the needle and looper shafts respectively to simultaneously operate said shafts.

10. A sewing machine comprising a frame with a work supporting arm along which the work is fed, and an overhanging needle arm; a needle shaft mounted on the needle arm; a looper shaft parallel with the needle shaft extending lengthwise of the work supporting arm; a drive shaft journaled in the frame crosswise of the needle shaft and the looper shaft in a plane below the latter and having a pair of rotary eccentric actuators thereon; pitmans extending upward

from one of said rotary eccentric actuators to the needle and looper shafts to simultaneously oscillate said shafts; and a third pitman extending upward from the other rotary eccentric actuator to the looper shaft to impart endwise or needle-avoiding movements thereto.

11. A sewing machine comprising a frame with a hollow base, a communicating hollow work supporting arm extending horizontally therefrom and a communicating hollow standard sustaining a needle arm over the work supporting arm; a needle shaft extending lengthwise of the needle arm into the hollow of the standard; a looper shaft extending lengthwise of the interior of the work arm in parallel relation to the needle shaft; a drive shaft journaled in the frame base crosswise of the needle shaft and the looper shaft in a plane below the latter and having a rotary eccentric actuator thereon; pitmans extending upward from said rotary actuator within the hollows of the column and the base to the needle and looper shafts respectively to simultaneously operate said shafts; and an oil sump in the base from which oil is taken and splashed about by said rotary actuator to lubricate the enclosed parts.

12. The invention according to claim 11, in which one end of the drive shaft protrudes through an oil-sealed bearing at one side of the base; and wherein the rotor of a looper thread control means is mounted on the protruding end of said drive shaft.

13. In a feed-on-the-arm sewing machine having a frame with a work supporting arm along which the work is fed, feeding means including a feed bar which extends lengthwise of the work supporting arm; a drive shaft disposed below and crosswise of the feed bar, and having a pair of eccentric actuators thereon; a rocker pivoted on the work supporting arm and having a pair of arms extending upward from the pivot for movement in the same direction, with one of said arms connected to the rear end of the feed bar; a link connecting one of the eccentric actuators to the other arm of the rocker so that lengthwise tension is induced both in said bar and in said link during the advancing movements of the feed bar; a rocker pivoted on the work supporting arm and having a pair of arms respectively extending horizontally and upward from its pivot, with its horizontal arm connected to the front end of the feed bar, and another link connecting the other eccentric actuator to the upstanding arm of the last mentioned rocker so that lengthwise tension is induced therein during the lift movements of said feed bar.

14. In a feed-on-the-arm sewing machine having a base with a laterally-extending work supporting arm along which the work is fed, feeding means including a feed bar which extends lengthwise of the work supporting arm; a rocker pivoted on the work supporting arm and having a pair of arms extending upward from the pivot for movement in the same direction, with one of said arms connected to the rear end of the feed bar; a rotary shaft disposed below and crosswise of the feed bar in the base and having an eccentric actuator thereon; and a link extending directly from the eccentric actuator on the drive shaft to the other arm of the rocker and connected to the latter so as to be under lengthwise tension during the advancing movements of said feed bar.

FREDERICK LUTZ.
